OVE L. GAMMELL AND ROLAND W. WOODWARD, OF ATTLEBORO, MASSACHUSETTS, AS
SIGNORS TO SMITH & CROSBY, OF NORTH ATTLEBORO, MASSACHUSETTS, A CO-
PARTNERSHIP COMPOSED OF ALFRED D. CROSBY AND GEORGE H. CROSBY.

BRACELET CONSTRUCTION.

Application filed April 6, 1928. Serial No. 267,849.

This invention relates to construction for bracelets and the like and more particularly to clasps or detachable connections therefor.

One of the objects of the invention is to provide a clasp or connector for bracelets and the like which affords a secure connection. Another object is to provide a device of the above nature which is convenient to operate for making and breaking the connection. Another object is to provide a device of the above nature which is well adapted for use in an extensible bracelet for wrist watches or the like and which may be made to harmonize with the other parts of the bracelet. Another object is to provide a construction of the above nature which is strong and durable. Other objects will be in part obvious or in part pointed out hereinafter.

The invention accordingly consists in the features of construction, combinations of elements and arrangements of parts, all as will be illustratively described herein, and the scope of the application of which will be indicated in the following claims.

In the accompanying drawing, in which is shown one of the various possible embodiments of this invention,

Fig. 1 is a plan view of the middle portion of a bracelet, showing the clasp closed and joining the bracelet ends together;

Fig. 2 is a side elevation of the parts shown in Fig. 1;

Fig. 3 is a section taken as indicated by the line 3—3 in Fig. 2 and showing the clasp or connector separated;

Fig. 4 is a section taken substantially as indicated by the line 4—4 in Fig. 3;

Fig. 5 is a section taken as indicated by the line 5—5 in Fig. 4;

Fig. 6 is an end view of the left-hand part of the clasp as viewed in the preceding figures; and

Fig. 7 is a perspective view of one of the parts.

Similar reference characters refer to similar parts throughout the several views of the drawing.

Referring now to the drawing in detail, the clasp or connector is shown employed in the middle of a bracelet which may be used as a

wrist watch bracelet. In Figs. 1 and 2, there are shown, at 10, 11, 12 and 13, respectively, four of the bracelet units which make up the body of the bracelet. These bracelet units are preferably identical in construction, and comprise an outer member and an inner sliding member, between which a spring acts tending to hold the sliding member within the outer member and to maintain the bracelet in contracted form. As may be seen in Figs. 1 to 4, each of the bracelet units preferably comprises an outer box-like member 14, within which is positioned a frame 15, the frame 15 having a pair of lugs or trunnions 16 which extend into recesses 17 in the side walls of the outer shells 14 and hold the frames 15 fixedly in position; also, within each of the outer members 14 is a sliding member 18 which is, as shown in Fig. 4, in the shape of a band having a top wall, a bottom wall and end walls. A coil spring 19 acts between an end wall of the member 18 and an end wall of the frame 15, tending to hold the sliding member 18 in retracted position within the outer member.

The frame 15 has at one end inwardly projecting fingers 15^a which project into the next adjoining unit and hook over the end wall of the sliding member 18 thereof to join the two bracelet units together. In this manner, an extensible bracelet is had, the inner sliding members 18 yielding against the action of the spring 19 and sliding out of their respective outer members to effect lengthening of the bracelet.

The construction of the bracelet units 10, 11, 12 and 13 need not be gone into in further detail herein because, in and of themselves, they do not form a part of the present invention. However, the invention is shown herein applied to a bracelet of this particular type and, in certain respects as will be pointed out more fully hereinafter, the invention achieves particular advantages in this relation.

Considering now the right-hand bracelet end, as viewed in the drawing, connected to the bracelet unit 12 is a bracelet unit 20, which is of substantially the same construction as the units 10, 11, 12 and 13, except that the

frame member 15 therein is slightly shorter so that the fingers 15^a do not project from the end of the outer shell 14. Within the bracelet unit 20 is a sliding link member 18, 5 which is substantially the same as the members 18 of the bracelet units forming the body of the bracelet, except that it is a little shorter, and within the unit is also a spring 19 acting between the frame 15 and the member 18, 10 tending to hold the member 18 in the retracted position shown. The fingers 15^a of the bracelet unit 12 engage the end wall of the sliding member 18 of the unit 20 to connect the units together.

15 Projecting outwardly from the unit 20 is a member 21, which is in the shape of a flat tongue. As shown in Fig. 4, the right-hand end of the member 21 projects within the unit 20, resting close against the top wall thereof, and has a downwardly projecting flange 22 which rests in back of the ears or fingers 15^a of the unit 20. Thus, the frame 15 of the end unit 20, built substantially as are the frames of the units forming the body of the bracelet, serves for the connection of the tongue 21.

Considering now the left-hand bracelet end, as viewed in the drawing, connected to the bracelet unit 14 is an end unit comprising an outer shell 23, which is preferably substantially identical with the outer shells of the other bracelet units. Within this member 23 is secured a member 24, which has an end wall 25 similar to the corresponding ends of the sliding link members 18. The fingers 15^a of the unit 14 take in back of this end wall 25 to connect the end unit 23 to the unit 14. The member 24 may be secured within the member 23 by soldering or any suitable securing means. As shown in Fig. 4, the member 24 rests against the bottom wall 23^a of the unit 23 at its two ends, the member being curved downwardly at 25^a near the end wall 25 and having at the other end a pair of downwardly extending lugs or flanges 26, the latter being shown more clearly in Fig. 6. Bent up from the body of the member 24 are two upstanding lugs or flanges 27 and 28, the upper ends of which are spaced from the inner side of the top wall 23^b.

55 Supported upon the upper side of the member 24 is a spring catch member which is most clearly seen in Fig. 3. This spring member is substantially U-shaped, comprising two arms 29 and 30 which extend along the inner sides of the side walls 23^c and 23^d, and a connecting part 31. The connecting part 31 of the spring member rests in back of the lug 27, and the spring member is secured in place by soldering between the part 31 and the part 27. 60 At their free ends the arms 29 and 30 have widened parts 29^a and 30^a, respectively, and at the inner sides of these two parts are a pair of upwardly projecting lugs 32 and 33. Also 65 extending from the parts 29^a and 30^a are fin-

ger pieces 34 and 35 which project outwardly through slots in the respective side walls 23^c and 23^d.

The tongue 21 attached to the end bracelet unit 21, as above described, is received between the wall 23^b and the arms 29 and 30 of the spring member, and it fits snugly between these parts, as shown in Fig. 5. Also, the tongue 21 fits closely between the side walls 23^c and 23^d, so that no transverse play 75 develops when the clasp is connected.

In the bottom surface of the tongue 21 is formed a longitudinal groove shaped as shown in dotted lines in Fig. 3. This groove 80 36 has a wide mouth at the end of the tongue 21, and the sides thereof converge in smooth curves until shoulders 37 and 38 are reached.

When the tongue 21 is moved into the end of unit 23, the lugs 32 and 33 come against and move along the inclined walls of the groove 36, thus drawing the two spring arms 29 and 30 together. When the tongue has been fully inserted, the lugs 32 and 33 snap in back of the shoulders 37 and 38, the arms 29 and 30 springing outwardly to the position shown in the drawing. When the tongue is inserted, the upper surface of the flange 28 on the member 24 rides along the base of the groove 36. At the end of the member 24 is an upwardly projecting flange 39, which is 95 of lesser height than the flanges 27 and 28. The upper edge of this flange 39 is substantially level with the upper surfaces of the spring arms 29 and 30 as shown in Fig. 6, and the bottom surface of the tongue 21 on either side of the groove 36 rides across this flange 39 and into place over the spring arms 29 and 30. As shown in Fig. 4, the tongue 21 is conveniently made in two parts, comprising an upper member 21^a and a bottom member 21^b, 100 the latter being shaped to provide the groove 36 and the shoulders 37 and the flange 22.

105 It will thus be seen that there is provided a construction of a simple and inexpensive character which embodies a secure fastening. In order to release the catch both of the lugs 34 and 35 must be pressed inwardly thus safeguarding against accidental detachment. On the other hand, intentional release is 110 readily achieved by the simultaneous pressure of the thumb and finger on these two lugs. The action is positive and the parts readily assembled and taken apart. Furthermore, the bracelet itself coacts with the features of the clasp to provide a neat and attractive appearance and to facilitate the anchorage of the clasp parts.

115 As many possible embodiments may be made of the above invention, and as many changes might be made in the embodiment above set forth, it is to be understood that all matter hereinbefore set forth or shown in the accompanying drawing, is to be interpreted as illustrative and not in a limiting sense.

We claim:

1. In construction for bracelets and the like, in combination, a bracelet end having a projecting tongue, a second bracelet end 5 adapted to receive said tongue and having side walls between which said tongue fits, and a spring catch member in said second bracelet end, comprising two opposed holding parts tending normally to spring outwardly from one another and finger pieces 10 thereon projecting outwardly through said side walls, said tongue having means thereon adapted to force said holding parts apart and interlock therewith to secure said bracelet 15 ends together.

2. In construction for bracelets and the like, in combination, a bracelet end having a top wall and side walls, a spring catch member therein extending laterally and spaced 20 from said top wall and comprising two opposed holding parts tending normally to spring outwardly from one another and finger pieces thereon projecting outwardly through said side walls, a second bracelet end having 25 a projecting tongue received between said catch member and said top wall, and means on the bottom side of said tongue adapted to force said holding parts apart and interlock therewith to secure said bracelet ends 30 together.

3. In construction for bracelets and the like, in combination, a bracelet end having a top wall and side walls, a spring catch member therein extending laterally and spaced 35 from said top wall, a second bracelet end having a projecting tongue received between said catch member and said top wall, and means on the bottom side of said tongue for cooperating with said catch member to secure said bracelet ends together, said catch member comprising a substantially U-shaped spring member having a pair of finger pieces projecting outwardly through the side walls of 40 said first bracelet end.

4. In construction for bracelets and the like, in combination, a bracelet end having a top wall and side walls, a spring catch member therein extending laterally and spaced from said top wall, a second bracelet 45 end having a projecting tongue received between said catch member and said top wall, and means on the bottom side of said tongue for cooperating with said catch member to secure said bracelet ends together, said

tongue fitting closely between said side walls to hold said bracelet ends against relative lateral swinging, and said catch member comprising two holding parts tending to spring outwardly toward the respective sides 50 of the bracelet and each having a finger piece extending through the respective side walls of said first bracelet end and adapted to be pressed inwardly to release said catch.

5. In construction for bracelets and the like, in combination, a hollow bracelet end,

a substantially U-shaped spring catch member therein, a second bracelet end having a projecting tongue received within said first bracelet end between a wall thereof and said spring catch, said tongue having in its surface facing toward said catch member a longitudinal groove narrowing from the outer end of said tongue and terminating in an inner widened part, said catch member having at its free ends a pair of lugs which 70 project into said groove and coact with said widened part to secure said bracelet ends together.

6. In construction for bracelets and the like, in combination, a hollow bracelet end, 80 a substantially U-shaped spring catch member therein, a second bracelet end having a projecting tongue received within said first bracelet end between a wall thereof and said spring catch, said tongue having in its surface facing toward said catch member a longitudinal groove narrowing from the outer end of said tongue and terminating in an inner widened part, said catch member 85 having at its free ends a pair of lugs which project into said groove and coact with said widened part to secure said bracelet ends together, and having a pair of finger pieces projecting outwardly through the side walls 90 of said first bracelet member and adapted to be pressed inwardly to bring said lugs into registry with the narrow end of said groove and permit said tongue to be drawn out for separating said bracelet ends.

7. In construction for bracelets and the like, in combination, a hollow bracelet end, a substantially U-shaped spring member in said bracelet end, the open end of said member facing toward the open end of said bracelet member, the arms of said spring member 100 tending to spring outwardly toward the sides of said bracelet member, a second bracelet end having a projecting part adapted to enter said first bracelet end, said projecting part having means adapted to coact 105 with said spring member to draw the two arms thereof toward each other as said part enters and to coact with said two arms to secure said two bracelet ends together when said projecting part has entered fully, and means for urging said two arms together to release said projecting part for separation of said bracelet ends.

8. In construction for bracelets and the like, in combination, a hollow bracelet end, 120 a substantially U-shaped spring member in said bracelet end, the open end of said member facing toward the open end of said bracelet member, the arms of said spring member tending to spring outwardly toward the sides of said bracelet member, and a second bracelet end having a projecting part adapted to enter said first bracelet end, said projecting part having means adapted to coact 125 with said spring member to draw the two 130

arms thereof toward each other as said part enters and to coact with said two arms to secure said two bracelet ends together when said projecting part has entered fully, said 5 arms of said U-shaped member each having a finger piece projecting through the respective sides of said hollow bracelet end and adapted to be pressed inwardly to release

said projecting part for separation of said bracelet ends. ¹⁰

In testimony whereof, we have signed our names to this specification this 29th day of March, 1928.

OVE L. GAMMELL.
ROLAND W. WOODWARD.
